UNITED STATES PATENT OFFICE.

FRITZ DEMEL, OF LONDON, ENGLAND.

SUBSTITUTE FOR GOLD-LEAF.

1,076,197.

Specification of Letters Patent.

Patented Oct. 21, 1913.

Original application filed May 1, 1911, Serial No. 624,227. Divided and this application filed August 14, 1912. Serial No. 715,134.

To all whom it may concern:

Be it known that I, FRITZ DEMEL, a subject of the German Emperor, residing in London, England, and whose post-office address is 63 Theobalds road, in the county of London, England, gold-beater, have invented a certain new and useful Substitute for Gold-Leaf, of which the following is a specification.

10 My invention, which is a division of my Patent No. 1,056,641, issued March 18th, 1913, consists in producing a substitute for gold leaf which possesses the properties essential for the applications of gold leaf, particularly in the book binding trade, 15 namely a degree of thinness sufficient for the production of clear impressions with fine lines and a low degree of coherence which renders it possible to remove with a 20 brush, for instance, such portions of the leaf as have not adhered to the surface to be covered.

Figure 1 is a perspective view of a portion of a forming plate on which a portion of a 25 sheet of gold leaf has been formed, and Fig. 2 is a perspective view of a portion of a sheet of gold leaf after it has been removed from the plate.

30 The mode of making the metal film consists as shown by Fig. 1 of the accompanying diagrammatic drawing in first coating a smooth surface, such as the surface of a glass plate *a*, with a thin layer *b* of an adhesive material, such as gutta-percha, applied in solution. When this layer *b* is dry 35 it is thoroughly brushed over with a metallic dust *c*, such as copper, to render it electrically conductive. On this metallic surface *c* a thin layer of metal *d*, such as nickel or 40 silver, is electrolytically deposited whereby the copper *c* is united to a sufficiently coherent surface. This done a layer *e* of gold

is electrolytically deposited on the surface of the layer of metal *d*. The plate thus coated is immersed in a solvent for gutta-percha, which solvent, however, is incapable of attacking metal. The gutta-percha *b* is then in whole or part removed by the solvent, and there is left as shown at Fig. 2, a metallic leaf *c*, *d*, *e* of the required properties, and carrying an amount of gold per unit area which may be considerably less than that contained per unit area of beaten gold leaf. The metallic leaf may be received on paper or the like as it leaves the 55 glass. Should a certain amount of gutta-percha remain on the back of the metal leaf, the leaf when employed for gold stamping can be used without any additional adhesive.

While I have herein described, and have 60 indicated on the drawings, particular materials which may be employed, I desire it understood that I do not limit myself to the use of these materials in all cases.

Having thus described my invention and 65 the best means I know of carrying the same into practical effect, I claim:—

A substitute for gold leaf consisting of a metallic film, a layer of metal deposit thereon and a layer of gold deposit on the 70 said layer of metal, the whole constituting an extremely thin leaf resembling gold leaf in its power of producing clear impressions with fine lines and in being so little coherent that portions which do not adhere to the 75 surface to which the leaf is applied can be removed by a brush.

In witness whereof I have signed my name to this specification in the presence of two subscribing witnesses.

FRITZ DEMEL.
